UNITED STATES PATENT OFFICE

1,965,089

APPARATUS FOR STORING AND TRANS-FUSING IGNITABLE LIQUIDS

Alois Weingessel, Maltheuern, Czechoslovakia

Application November 5, 1932, Serial No. 641,366
In Czechoslovakia February 11, 1932

4 Claims. (Cl. 221—11)

This invention relates to an arrangement for storing and transfusing ignitable liquids, and its chief object is to allow to safely keep and handle such liquids, as for example, pouring them in, 5 and out of, containers. This is obtained by connecting the interior of a container with the atmosphere by at least one coiled tube. Tests have proved that a fire caught at the mouth of a container or in the surrounding of such container 10 provided with an arrangement according to the invention cannot penetrate into the interior of the said container. On the other hand, it is possible, by means of the arrangement according to the invention, to discharge a burning tank 15 or container by transfusing the liquid through such coiled tube into another container, whereby the main part, if not all, of the contents of the burning tank can be saved.

The coiled tube is preferably formed so that 20 in each position, a siphon-like closure for the liquid is provided.

Another advantage can be obtained by providing on a container one coiled tube for the admission of liquid, another coiled tube for the 25 discharge of the liquid, and, if required, a third coiled tube for the admission of air into the container.

In the drawing an embodiment of the invention is shown by way of example, in which a relatively small container is illustrated. The arrangement according to my invention may, however, be with advantage attached to a large tank 30 or reservoir.

1 is the container having the shape of a can 35 or jug. At 2 is the inlet hole which merges into a coiled tube 3 ending in a lid 4 at the bottom. At 5 is the outlet hole connected with the interior of the container by means of the coiled tube 6. For the purpose of admission of air into 40 the container, a coiled tube 7 is provided, which at 8 ends into the open, this port being adapted if desired to be closed by a closing member 9. If such a container is for example, used as a tank in motor cars, it is possible, in case the carburetor has caught fire, to stop the feeding of fuel 45 to the engine by closing the closing member 9 through operation of the switchboard. The coiled tubes, in particular, tubes 3 and 6 are suitably given a shape which in every position of 50 the coiled tube, provides for a siphon-like closure for the liquid. As shown in the drawing, this is obtained by replacing the usual spiral shape of the coiled tube by a structure in which a downwardly bent portion is connected to an upwardly bent portion and vice versa, so that a

pool of liquid is permanently being formed. If now the liquid is to be poured out, it will not flow out until all the coils are filled with liquid, so that no air can penetrate into the interior

According to the invention, the container may 60 also dwindle into a simple funnel to which a coiled tube is connected. In this manner it is possible to pour burning liquid into such device, and securely pour it into a container provided below the said device. If a cistern is connected 65 by such arrangement with an empty reserve cistern the liquid may be transfused in the case of an ignition.

What I claim is:—

1. The combination with a liquid container 70 adapted to discharge its liquid by tilting and having a discharge opening adjacent its bottom, of a discharge tube outside said container and connected with said opening and extending upwardly to a point above the liquid level in said 75 container when it is full, said tube having a plurality of loops below said level having in all positions of tilting of said container a tube portion at a lower level than tube portions on both sides of it whereby the passage through the tube 80 is always closed by the liquid.

2. The combination with a liquid container adapted to discharge liquid by tilting and having a discharge opening adjacent the bottom thereof, of a discharge tube outside said container and connected with said opening and extending upwardly to a point above the liquid level in said 85 container when it is full, said tube being reflexed and in the vertical position of said container comprising laterally extending loops 90 below said level each including a space wider upon its interior than at its mouth.

3. The combination with a liquid container adapted to discharge liquid by tilting having a discharge opening adjacent its bottom and an 95 intake opening adjacent its top, of intake and discharge tubes outside said container and connected respectively with said intake and discharge openings, said discharge tube extending upwardly to a point above the liquid level in said container 100 when it is full and said intake tube extending upwardly from the intake opening, each of said tubes having a plurality of loops having in all positions of tilting of said container a tube portion at a lower level than tube portions on both sides of it whereby the passage through the tube 105 is always closed by the liquid, said discharge tube having its loops below the liquid level of the container when it is full.

4. The combination with a liquid container 110

adapted to discharge liquid by tilting having a discharge opening adjacent its bottom and an intake opening adjacent its top, of intake and discharge tubes outside said container and connected respectively with said intake and discharge openings, said discharge tube extending upwardly to a point above the liquid level in said container when it is full and said intake tube extending

upwardly from the intake opening, each of said tubes being reflexed and having, in the vertical position of the container, laterally extending loops each including a space wider upon its interior than at its mouth, the loops in said discharge tube being below the liquid level of the container when it is full.
